ELECTRIC SHAVER LIGHT

Lester L. Perry, Denver, Colo.

Application October 7, 1946, Serial No. 701,775

3 Claims. (Cl. 240—2)

1

The present invention relates to dry shavers and more particularly to dry shavers which are provided with means, either forming a part thereof, or detachably connected to or mounted thereupon, for the purpose of illuminating the surface to be contacted and shaved by the dry shaver.

Various illuminating means with dry shavers have been provided, some of which have been satisfactory from the standpoint of use, but none, or at least only a few of which have been wholly satisfactory from the manufacturing standpoint. This was due to the fact that in many instances special lamp bulbs or built-in resistance elements, all requiring manufacturing changes in the design of any present shaver were required, because of the fact that the shaver motor required a current voltage of from 110 to 115 volts, whereas the relatively small and low voltage incandescent lamp bulb could only operate properly with an extremely low voltage current. Moreover, in accordance with some prior art devices, portable battery-powered lamp bulbs were employed to illuminate the surface to be shaved. Such devices were obviously bulky and cumbersome to handle. Other devices of the prior art required special bulbs and interference with the motor wiring so as to illuminate the bulb properly from the same source of current which flowed to the magnetic type motor for operating the shaver.

One of the objects of the present invention is to provide an improved dry shaver having improved illuminating means for the surface to be shaved, which device does not have any of the objectionable features, some of which have been described above, of the previously known devices of this general nature.

Another object of the invention is to provide a compact and relatively light shaver structure in which an adapter member attached to a three wire cord, one wire of which has the proper ohm resistance to reduce the voltage from the 110 to 115 volts required for the shaver to the 6-8 volts required for the radio panel light bulb, is associated with the structure for the purpose of adapting the normal electric current of from 110 to 115 volts for operating the shaver motor, for use in illuminating the low voltage lamp bulb with which the shaver is equipped.

Another object of the present invention is to provide an improved shaver structure in which the illuminating means and the voltage adapter member or plug may be clamped onto the shaver casing and removed therefrom with ease and facility.

2

Another object of the present invention is to provide an improved dry shaver having means for illuminating the surface to be shaved, which is capable of employing a standard or conventional 6 volt radio lamp bulb of the type normally used for illuminating a radio dial; it being another object of the present invention to provide the shaver with a low voltage adapter plug fitting in the circuit and permitting the use of the 6 volt radio bulb and thus serving to interconnect a three-wire detachable electric connection plug with the shaver motor and illuminating means.

Another object of the present invention is to provide an improved shaver of the foregoing character in which the lamp bulb for illuminating the surface to be shaved, while being protected by a hood, is readily removable from the shaver structure for purposes of removal or replacement.

A further object of the invention is to provide an improved shaver having a two-part or two-section casing and improved illuminating means, in which the illuminating means may be installed as a part of the assembly without requiring any manufacturing changes except for the upper part, half or section of the casing.

A further object is to provide a shaver having improved illuminating means which may be applied to the standard or conventional shaver casing of any make or brand of shaver, and removed therefrom, without requiring or necessitating any manufacturing changes whatsoever in the shaver structure.

Another object of the invention is to provide a low voltage lamp bulb having a socket fitting within a hood or reflector recess formed in the shaver casing, in which the bulb socket has a sliding friction fit permitting it and the bulb to be removed when and if desired.

The foregoing and other objects and advantages of the present invention will be apparent from the following description and appended claims when considered in connection with the accompanying drawings forming a part of this specification and wherein like reference characters designate corresponding parts in several views.

In said drawings:

Fig. 1 is a side elevational view, partly in section, of one form of dry shaver embodying the present invention.

Fig. 2 is a front elevational view of the structure shown in Fig. 1.

Fig. 3 is a side elevational view, partly in section, of another form of the present invention

in which the illuminating means is clipped or clamped onto the shaver casing and thus removable therefrom.

Fig. 4 is a front elevational view of the shaver of Fig. 3.

Fig. 5 is a longitudinal vertical sectional view through the length connection plug and low voltage adapter member of the preceding views, the parts being shown in separated condition.

Fig. 6 is a vertical sectional view taken substantially along the line 6—6 of Fig. 5, looking in the direction of the arrows; and

Fig. 7 is a schematic diagram of the electrical circuit illustrating particularly the functional relationship of the low voltage adapter member and the three-wire detachable electric connection plug.

Before explaining in detail the present invention it is to be understood that the invention is not limited in its application to the details of construction and arrangement of parts illustrated in the accompanying drawing, since the invention is capable of other embodiments and of being practiced or carried out in various ways. Also it is to be understood that the phraseology or terminology employed herein is for the purpose of description and not of limitation.

Referring now particularly to the drawings, in Figs. 1 and 2 thereof the dry shaver of the present invention is shown in one of its forms in which it comprises a two-part casing or housing 10 as indicated at 10a, within which is located an electric motor of the magnetic type and adapted to be operated upon the usual house current having a voltage of from 110 to 115 volts. At one end portion the casing 10 is provided with a shaving head 11 and carries on its upper side or surface a preferably centrally disposed longitudinally extending sub-casing or housing 12 which may or may not be formed integrally with the main housing or casing 10. The forward end of the sub-casing 12 is in the form of a hood or reflector 12b providing a preferably circular recess 13, the hood having a longitudinal guideway or slot 13a formed therein. The recess receives the socket 14 of a low voltage electric lamp bulb, such as a 6 to 8 volt conventional radio lamp bulb 15, which is threadedly engaged in the socket. The socket 14 is formed of such a size as to have a sliding friction fit in the recess 13 and has a guide rib or projection 14a which registers with and is adapted to slide in the guideway 13a. The friction fit prevents the electric lamp and its socket from becoming accidentally displaced from the recess yet permits the lamp and its socket to be removed, as indicated in broken lines in Fig. 1, to permit the removal or replacement of the lamp bulb. To permit this freedom of movement within the recess in the hood 12b and to be removable therefrom, the electric wires 16 leading to the lamp bulb and its socket are provided with a slack portion or surplus at 16a.

At the rear end of the body or casing 10, there is provided a low voltage adapter member or plug 17 carrying the wires 16, previously referred to. This adapter member or plug is chamfered or beveled at its forward portion 18 to interfit with the adjacent or rear end portion 12c of the auxiliary or sub-casing 12, so as to make a snug fit therewith. The under surface 19 of the member or plug is shaped so as to lie flat upon the adjacent or rear end portion of the casing 10. The wires 16 terminate at the rear end of the adapter member or plug 17 in fixed contact points or pins 16b, one such being shown in Fig. 5.

A three-wire detachable electric connection plug 20 is applied to the rear end of the casing and its upper portion or section has sockets 21a and 21b (see Figs. 5 and 6) to receive the contact pins 16b of the adapter plug. This connection plug or member 20 is provided in its lower forward portion or section with similar sockets 22 to receive contact pins or members (not shown) projecting outwardly from the rear or inner end of the shaver casing 10, these providing the electrical connections for current which flows to the magnetic type motor housed within the casing 10.

The plug 20 carries a cable or conduit 20a containing a wire 20b carrying 110 to 115 volt current, a "Nichrome" or equivalent resistance wire 20c of proper ohms resistance, such as 390 ohms resistance, to reduce voltage from 110 to 115 to 6 to 8 volts, and a third wire 20d common to both wires 20b and 20c. It is to be understood that the 110-115 volt wire 20b and the so-called common wire 20d are electrically connected through sockets 22 and pin contacts (not shown) to the electric motor (not shown) in the two-part casing 10. Wire 20d is also electrically connected, with the addition of resistance wire 20c to sockets 21a and 21b and pin contacts 16b, etc., and to the lamp bulb 15.

It will be understood that the plug member or connection 20 is detachably connected to the rear end of the casing 10 and also to the interconnecting low voltage adapter member or plug 17. This plug 20 also acts as a stabilizer to hold the lamp assembly, including the sub-casing 12, against movement on the casing 10.

It is to be understood that the recess 13 formed in the hood portion 12b of the sub-housing or casing 12, provides not only a space for the lamp bulb 15 and its socket but also serves as a reflector for the rays of light emitted by the bulb, which latter are directed onto the surface to be shaved.

It will be understood, of course, that if desired, the adapter member or plug 17 may be formed integrally with the casing 10 and sub-casing 12, or may be a separate member and detachable therefrom, as indicated in Fig. 1.

In Figs. 3 and 4 of the drawings there is shown a somewhat modified form of the present invention. In this form of the invention, the casing or housing 10 of the shaver has clipped or clamped onto its top side, an auxiliary or sub-casing or housing 12, generally like that of the preceding form of the invention. The sub-casing or auxiliary housing 12 of this form is, however, provided with a clip, clamp, or band member 12a, which permits the auxiliary casing 12 to be removably attached to the shaver casing 10. The adapter member or plug 17 and the detachable electric connection plug 20 of the present form are substantially the same as those of the preceding form. The adapter member 17 may or may not be formed as an integral part of the auxiliary casing or sub-housing 12 of Figs. 3 and 4.

As in the preceding form of the invention, the electric lamp bulb 15 is preferably of 6 to 8 volt power and is a standard or conventional radio lamp bulb which may be used by virtue of the provision of the adapter member or plug 17 and the resistance wire connected thereto.

From the foregoing it will be seen that I have provided an improved dry shaver having improved means for illuminating the surface to be shaved, in which the illuminating means and its casing or housing may be formed as a part of

the shaver casing or housing or may be detachably supported on the latter by means of a clamp, clip, or in any other suitable manner, so that it may be applied to or removed from the shaver casing proper with ease and facility. It will also be understood that by virtue of the present invention, the normal 110 to 115 volt electric current may be employed to operate the shaver motor and to also illuminate the lamp bulb, this because of the provision of the adapter member or plug 17.

The term "dry shaver" as used herein is to be understood to apply as well to other similar appliances of various sorts such, for example, as electric clippers used by barbers, etc.

Having thus described the invention, what is claimed is:

1. An electric shaver comprising a casing, an electric motor within said casing, a shaving head at the forward end of said casing operably connected to said motor, a pair of electrical contacts at the rear end of said casing operably connected to said motor, a hood mounted on said casing, a low voltage bulb mounted in a socket in the forward end of said hood to project light toward said shaving head, a pair of wires extending rearwardly from said socket through said hood, a low voltage adapter member having wires secured to said socket wires, an electrical connection plug having a pair of low voltage connections adapted to engage said low voltage adapter member to complete the low voltage circuit through the member, said connection plug also having a pair of normal voltage connections adapted to engage said electrical contacts, a conduit comprising a pair of low resistance wires and a high resistance wire, said low resistance wires being connected to said normal voltage connections, said high resistance wire and one of said low resistance wires being connected to said low voltage connections.

2. An illuminating device for an electric shaver having a casing and motor contacts, comprising a hood surmounting and forming a fixed part of the casing of said shaver, a low voltage bulb mounted in one end of said hood to illuminate the

working zone of said shaver, a low voltage adapter member electrically connected to said bulb and detachably connected to said hood, a connection plug having a pair of normal contacts adapted to engage the conventional motor contacts of said shaver and a pair of low voltage contacts adapted to engage said low voltage adapter member and a three-wire conduit connected to said connection plug supplying normal voltage to said normal voltage contacts and low voltage to said low voltage contacts.

3. An illuminating device for an electric shaver having a casing comprising a hood mounted on said casing, a substantially cylindrical portion in one end of said hood adjacent the working zone of said shaver, a bulb socket frictionally engaging said cylindrical portion, an adapter member removably engaged in the other end of said hood, and a slack wire connection between said adapter member and said bulb socket whereby said bulb socket may be removed from said hood for insertion or removal of a bulb, said cylindrical portion being provided with a longitudinal guideway, said bulb socket being provided with a guide rib slidably engaging said guideway and said cylindrical portion also forming a reflector for the light rays emitted from said bulb.
